UNITED STATES PATENT OFFICE.

NILS DAVID LEVIN, OF COLUMBUS, OHIO, ASSIGNOR TO THE JEFFREY MANUFACTURING COMPANY, OF COLUMBUS, OHIO, A CORPORATION OF OHIO.

MINING-MACHINE AND TRUCK.

1,247,424.

Specification of Letters Patent. Patented Nov. 20, 1917.

Application filed March 17, 1914. Serial No. 825,369. Renewed June 30, 1917. Serial No. 177,965.

To all whom it may concern:

Be it known that I, NILS DAVID LEVIN, citizen of the United States, residing at Columbus, in the county of Franklin and State 5 of Ohio, have invented certain new and useful Improvements in Mining-Machines and Trucks, of which the following is a specification, reference being had therein to the accompanying drawing.

10 My present invention relates to certain new and useful improvements in mining machines and trucks for the transportation of said machines about the rooms and galleries of the mine, and especially to trucks 15 which are propelled along the tracks of the mine by power derived from the motor of the mining machine being transported.

I am aware that trucks of this character have been heretofore proposed, my especial 20 objects being to provide improved means for connecting the motive power of the mining machine with the transmission gearing of the trucks; to provide a truck having an electric cable reel with improved gearing 25 for transmitting power to the track wheels and to the reel; to provide improved means for controlling the movements of the truck along the mine tracks; and to provide improved facilities for loading and unloading 30 the mining machine. The foregoing objects, and others more or less ancillary to them, are attained in the structure set forth in the annexed specification in connection with the accompanying drawings.

35 In the drawings,

Figure 1 is a plan view of a truck embodying my invention;

Fig. 2 is a side elevation of the truck shown in Fig. 1, and of the mining machine 40 (shown in dotted outline) loaded thereon for transportation;

Fig. 3 is a vertical section on the line 3—3 of Fig. 1;

Fig. 4 is a vertical section on the line 4—4 45 of Fig. 1;

Fig. 5 is a section on the line 5—5 of Fig. 4;

Fig. 6 is a side elevation of the truck in position for loading the mining machine.

50 There are several types of machine in use for the undercutting of coal to facilitate its being broken down for removal from the mine. One of the most common in use at the present time comprises a base frame, 55 adapted to slide over the floor of the mine,

from the forward end of which projects a cutter arm having a cutter chain with renewable bits adapted to cut the coal. Such machines are usually provided with winding drums having ropes adapted to be anchored to suitable abutments, and in operation the machines are propelled and guided along the face of the coal by the winding in and paying out of the ropes. After the entire length of the working face has been undercut it is desirable that the machine shall be loaded upon a truck and transported to another working place where it shall be unloaded and put to work with as little delay as possible.

60 In my present invention I have produced such a truck having a frame composed of two longitudinal angle bars 1 joined by cross members 2, 3 and 4 and by the transmission gear case casting 5. Suitable axle boxes 6 65 are bolted to these longitudinal angle bars and in these are journaled the axles 7 and 8 having wheels 9 adapted to travel along the rails 10 of the mine track. The axles 7 and 8 are coupled together by an endless 70 chain 11 engaging suitable sprocket wheels carried by the wheels.

75 Extending transversely of the truck frame, within the gear case 12, is a driving shaft 13 which is driven from the mining machine 80 motor as will presently appear. On one end of the shaft 13 is mounted for free rotation a sprocket wheel 14 having an inwardly projecting hub 15 which is journaled in the bearing 16 of the gear case 12, 85 and has on its inner end clutch teeth 17 engageable with similar teeth of the clutch member 18 splined to the shaft. The sprocket wheel 14 is connected by a chain 19 and sprocket wheel 20 to the axle 8 to propel the truck. Means for shifting the clutch member 18 into and out of engagement with the sprocket wheel 14 is provided in a yoke 90 95 attached to a shaft 22 extending through the walls of the gear case 12 and having a hand lever 23 convenient to the hand of the operator.

100 The shaft 13 is supported at its other end in a bearing 24 of the gear case. Mounted for free rotation upon the shaft 13, adjacent the bearing 24 is a sheave wheel 25 which is connectible to the said shaft by a pin clutch comprising a pin 26 slidable in apertures of the hub 27 and in a lug 28 formed on the rim of the wheel. Surrounding the pin 26 110

is a coiled spring 29 the outer end of which abuts against the lug 28 while the inner end bears against the handle 30 which is secured to the pin, and by which it may be manipulated. The spring 29 tends to force the pin 26 inward to engage an aperture 31 of the shaft 13. When it is desired that the wheel 25 shall not be rotated by the shaft 13 the pin 26 may be forced outward to disengage 10 the aperture 31 and locked in that position by rotating the handle 30 into engagement with a lug 25^a formed on the wheel 25 to retain it. The sheave 25 is connected by an endless rope 32 to drive a sheave 33 attached to the spindle of a removable cable reel 34 adapted to wind the electric conductor cable 35 by which power to drive the machine is brought from the wiring system of the mine. The cable reel 34 has its shaft 20 34^a journaled in bearing boxes 36 carried by a yoke frame 37 the lower end of which bears in notches of the angle irons 38 which are secured to the platform 39 of the truck. The center of gravity of the reel 34 is disposed to one side of the pivotal support of the frame 37 in the notches of the irons 38, and consequently a part of the weight of the cable reel 34 is carried by the rope and a sufficient tension is maintained therein 25 to properly drive the cable reel to wind the cable 35. A plurality of notches are provided in the angle irons 38 to allow a measure of adjustment of such tension. One of the boxes 36 has within it the mechanism 35 for gathering the positive current from the positive conductor of the cable 35, and the other box is similarly adapted to collect current from the negative conductor of the cable 35. 40 is a flexible cable having conductors 40^a, 40^b, which lead, respectively, from the terminals in the two bearing boxes to the corresponding terminals of the mining machine motor.

Mounted for free rotation upon the transverse shaft 13 are two bevel gears 41, 41 both meshing with a bevel pinion 42 formed on the rearward end of a sleeve 43 journaled in a bearing 44 of the gear case 12. Slidable within the sleeve 43 but rotatably connected thereto, is a shaft 45 which is journaled in a bearing 46. Keyed to the shaft 45 adjacent to the forward end of the bearing 46 is a bevel pinion 47 adapted to mesh with a gear 48 of the mining machine when it is in 55 proper position upon the track. A collar 49 pinned to the shaft 45 adjacent the rear end of the bearing 46, secures the shaft against longitudinal movement relative to the bearing 46. Formed on the sides of the bearing 46 are wings 50 slidable in guides 51 formed at the ends of the arms 52 extending from the gear case 12. One of these wings 50 and the corresponding guide are perforated with registering apertures adapted to receive the

pin 51^a to lock the bearing from movement 65 relative to the guide way.

After the mining machine is in position upon the truck the pin 51^a is withdrawn, the bearing 46 and shaft 45 moved forward to bring the pinion 47 into engagement with the gear 48 of the mining machine and the pin again inserted to maintain the parts in working relation. When the truck has arrived at the place where the machine is to be unloaded, the pin is again withdrawn, 75 the bearing 46 and pinion 47 moved to their disengaging position and the pin again inserted.

The bevel gears 41, 41 are connectible to the shaft 13 through multiple disk friction 80 clutches to drive it, the direction of rotation depending upon which of the gears is brought into service. As the friction clutches are identical in construction, a description of one will suffice for both. 85

Formed on the back of each of these bevel gears 41, 41, is a cylindrical extension 53 having a plurality of longitudinal ribs formed on its inner side, and within this cylindrical extension is a clutch member 54 90 keyed to the shaft 13 and having on its outer side a plurality of longitudinal ribs. Between the cylindrical extension 53 and the member 54 are arranged a series of driving and driven disks 55 having notches that 95 engage the ribs on the parts 53 and 54, respectively. Slidable on the hub of the clutch member 54 is a pressure member 56 adapted to press the friction disks together. Positioned adjacent the hub of the pressure 100 member 56 is a thrust collar 57 adapted to transmit the pressure of the shifting yoke 58 to the pressure member and through it to the disks of the clutch to drive the shaft, a suitable antifriction bearing 59 being interposed between the collar 57 and the pressure member. Positioned between the wheels 41, 41 on the shaft 13 is an antifriction bearing 60 supported in a bearing 61 of the gear case to which it transmits the 110 thrust of the friction clutches.

The shifter yoke 58 is double ended, having a fork at each end adapted to engage the sliding collars 57 by which the ball bearings 59 are pressed against the pressure 115 members 56. Formed at the middle of the shifting yoke 58 is an extension 63 which projects upward through a suitable aperture in the gear case 12, and is formed near its upper end with an aperture through which extends a push rod 64. The push rod 64 is screw threaded to receive the nuts 65 and 66 engaging the springs 67 and 68 which abut against the extension 63. Formed at the end of the rod 64 is an eccentric 120 strap 69 coöperating with the eccentric 70 to shift the yoke 58 and with it the pressure members of the friction clutches. The ec-

centric 70 is journaled on a stud 71 attached to the gear case 12, and rotated thereon by a hand lever 72 convenient to the hand of the operator. Pins 73 are provided to limit the rotation of the eccentric.

Pivoted at 74 on the truck frame are two angle bars 75 connected together at their free ends by a cross bar 76 to form a support for the rear end of the truck frame 10 when it is tilted to bring the forward end into position for loading the mining machine. Pivoted to one of these angle bars 75 is a bar 77 having a longitudinal slot 78 on the side of which is formed a plurality 15 of notches adapted to engage with a stud 79 projecting from the truck frame and serving to retain the bars 75 in any desired position. A hook 80 is provided to hold the cross bar 76 clear of the track while the 20 truck is traveling from room to room.

Formed on the gear case 12 is an upstanding flange 81 having in its forward side a notch 82 adapted to engage the terminal 25 of the feed rope 83 of the mining machine, to afford convenient anchorage therefor when pulling the machine upon the truck.

The operation of the truck is as follows: The undercutting of the coal at a given place being completed and the machine required at a distant place, the rope 83 is secured in the notch 82 of the flange 81, the rear end of the truck elevated, the truck support adjusted and the winding drum of the mining machine started. As the rope is wound 35 up, the machine, guided by the flanges of the longitudinal angle bars 1, will be drawn to its proper place on the truck. The rear end of the truck will then be lowered and the support secured by the hook 80, the bearing 40 46 adjusted to connect the pinion 47 with the gear 48, the removable cable reel 34 loaded and its driving rope 32 adjusted. The machine will then be ready for traveling. After the mining machine motor is 45 started the control of the truck is effected entirely by the eccentric lever 72, which will be turned to one side for forward movement, to the other side for reverse and in the middle to disconnect the power. No brakes are 50 provided as the motion of the truck can be retarded by applying power in a reverse direction by a simple manipulation of the hand lever 72.

When the machine has arrived at the desired location the rear truck support is unhooked and allowed to rest on the track rails, the cable reel is removed, the pinion 47 drawn back out of mesh with the gear 48, and the rope 83 attached to some suitable anchorage to pull the machine from the truck. As the machine moves forward the truck will be tilted on the forward wheels and the rear support will fall into place and be automatically locked by the

bar 77 to prevent the truck falling back as the machine passes off its forward end.

What I claim is:—

1. The combination with a mining machine having power driven gearing, of a truck therefor having a frame adapted to support the mining machine, wheels supporting the frame, and gearing on the frame for transmitting power to the truck wheels comprising a movably mounted gear adapted to be moved from an inoperative position 75 into mesh with a gear on the mining machine after the latter has been moved into position for transportation upon the truck.

2. The combination with a mining machine having power driven gearing, of a truck therefor having a frame adapted to support the mining machine, wheels supporting the frame, and gearing on the frame for transmitting power to the truck wheels comprising a gear mounted so as to permit 85 its axial movement from an inoperative position into mesh with a gear of the mining machine after the latter has been moved into position for transportation upon the truck.

90

3. The combination with a mining machine comprising an electric motor and gearing driven thereby, of a truck for the mining machine having a frame adapted to support it, wheels supporting the frame, an electric cable reel mounted on the truck, an electric cable arranged to be wound upon and paid out from said reel, flexible conductors connecting the terminals of the cable reel with the terminals of the motor, and transmission gearing on the truck adapted to drive the truck wheels and the cable reel in unison, said transmission gearing comprising a member adapted to engage with and be driven by a member of the mining machine gearing, a clutch interposed between the said driven member and the reel, and a second clutch interposed between the said driven member and the track wheels whereby the track wheels and the cable reel 110 can be driven in unison or either can be driven independently of the other.

4. In a mining machine truck, the combination of a frame adapted to support a mining machine, wheels supporting said frame, and a support pivotally connected to the truck frame near one end thereof and adapted when the said end of the truck frame is lifted to move automatically into position to support the lifted end of the truck frame 120 from the ground.

5. In a mining machine truck, the combination of a frame adapted to support a mining machine, wheels supporting said frame, a support pivotally connected to the truck frame near one end thereof and adapted when the said end of the frame is lifted to move automatically into position to support

125

the frame from the ground, and means for securing the support in operative position.

6. In a mining machine truck, the combination of a frame adapted to support a mining machine, wheels supporting said frame, a support pivotally connected to the truck frame near one end thereof, and means normally securing the support in inoperative position but adapted to release the support, 10 said support when released being adapted when the said end of the truck frame is lifted to move automatically into position to support the said end of the frame from the ground.

15 7. In a mining machine truck, the combination of a frame adapted to support a mining machine, wheels supporting said frame, a strut-like support pivotally connected to the truck frame near one end thereof and 20 adapted to swing downward into position to support the end of the truck from the ground when said end is lifted, and means for normally securing the support in a raised, inoperative position.

25 8. The combination with a mining machine having power driven gearing, of a truck therefor having a frame adapted to support the mining machine, wheels supporting the frame, gearing on the frame for 30 transmitting power to the truck wheels comprising a movably mounted gear adapted to

be moved from an inoperative position into mesh with a gear on the mining machine after the latter has been moved into position for transportation upon the truck, and 35 means for securing the movably mounted gear in operative and inoperative positions.

9. The combination with a mining machine comprising an electric motor and gearing driven thereby, of a truck for the 40 mining machine having a frame adapted to support it, wheels supporting the frame, an electric cable reel mounted on the truck, an electric cable arranged to be wound upon and paid out from said reel, flexible conductors connecting the terminals of the cable reel with the terminals of the motor, and gearing on the truck adapted to transmit the power of the motor to the truck 45 wheels and to the cable reel, the train of 50 gearing transmitting the power of the motor to the truck wheels comprising reversing gearing in which the power is transmitted through friction clutches, substantially as 55 and for the purpose set forth.

In testimony whereof, I affix my signature, in presence of two witnesses.

NILS DAVID LEVIN.
